SPOOL GLUING AND ASSEMBLING MACHINE.

No. 842,169.

Specification of Letters Patent.

Patented Jan. 29, 1907.

Application filed May 18, 1905. Serial No. 261,061.

To all whom it may concern:

Be it known that I, IRA A. BLOOD, a citizen of the United States, residing at Methuen, in the county of Essex and State of Massachusetts, have invented a new and useful Improvement in Spool Gluing and Assembling Machines, of which the following is a specification.

This invention has reference to an improvement in bobbin gluing and assembling machines adapted for gluing the heads of spools and assembling the spools by screwing the glued heads onto the ends of the spool-cylinders.

15 In the process of manufacturing wooden spools the heads on the ends of the cylinders have heretofore been glued by hand and the cylinder and heads assembled to form a complete spool by screwing the heads onto the 20 ends of the cylinder by hand. This method of gluing and assembling the spool by hand is slow, laborious, and expensive to the manufacturer.

25 The objects of my invention are to glue and assemble spools more expeditiously and at a lower cost than has heretofore been done, and I accomplish these objects by providing a machine that will feed and glue the spool-heads automatically and assemble by screwing the glued heads onto the ends of the 30 spool-cylinder to form a complete spool by the single operation of a lever.

35 My invention consists in the peculiar and novel construction of a spool gluing and assembling machine adapted to automatically feed and glue the heads of spools, and when the cylinder and heads are placed in their proper position in the machine by the operator to assemble by screwing the glued 40 heads onto the ends of the cylinder in one operation of a lever, as will be more fully set forth hereinafter.

45 Figure 1 is a front view of my improved spool gluing and assembling machine, showing the gluing mechanism in the position it would assume in gluing the heads of a spool and the assembling mechanism in the position for assembling by screwing the heads onto the ends of a spool-cylinder, (shown in 50 broken lines.) Fig. 2 is a top plan view of the machine with the operative parts in the same position as shown in Fig. 1. Fig. 3 is an enlarged detail sectional view taken on

line X X of Fig. 1 through the hopper, showing the means for adjusting the hopper for 55 different sizes of spool-heads. Fig. 4 is a vertical transverse sectional view taken on line Y Y of Fig. 1, showing the feeding and gluing mechanism operatively connected with the assembling mechanism. Fig. 5 is 60 an enlarged detail sectional view through the spool-head-feed mechanism, showing a feed-slide in its normal or outward position. Fig. 6 is an enlarged transverse sectional view taken on line Z Z of Fig. 1 through the 65 glue-pot, showing the glue-cups in the position they would assume in gluing the heads in full lines and the position they would assume in the glue for filling the cups with glue in broken lines. Fig. 7 is an enlarged sectional view of one of the glue-cups, showing the outlet-holes in the side of the cup and the means for securing the cups to the supporting-frame; and Fig. 8 is a sectional view taken lengthwise through a completed spool. 75

In the drawings, *a* indicates the double frame; *b*, the gravity-hopper for the spool-heads; *c*, the spool-head-feed mechanism; *d*, the spool-head-gluing mechanism; *e*, the actuating mechanism for the feed mechanism *c* and the gluing mechanism *d*; *f*, the glue-pot; *f'*, the glue in the glue-pot; *g*, a gas-burner; *h*, the head-stock of the assembling mechanism; *i*, the tail-stock; *k*, the release-arm; *l*, the operating-lever of my improved 85 spool gluing and assembling machine, and *m* a spool consisting of the cylinder *m'*, having the longitudinal hole *m'*, the screw-threaded ends *m*³ *m*³, and the circular heads *m*⁴ *m*⁴, having the central screw-threaded holes *m*⁵ *m*⁵. 90

The double frame *a* is formed in two parts for convenience of construction. They may be secured together and to the floor, if required. The part *a'* consists of a bed *a*², supported on the four legs *a*³ *a*³, as shown in 95 Figs. 1 and 4. The bed *a*² has the closed top *a*⁴, in which are the longitudinal slots *a*⁵ *a*⁵, in the edge of which are the ways *a*⁶ *a*⁶ for the feed-slides, the two circular holes *a*⁷ *a*⁷ for the glue-cups, and the apertures *a*⁸ *a*⁸ for the frame of the glue-cups, as shown in Fig. 6. A portion of the top *a*⁴ is formed into the removable cover *a*⁹, secured to the frame by the thumb-nut bolts *a*¹⁰ *a*¹⁰. These bolts are pivotally secured to the cover and engage 100 with the bifurcated lugs *a*¹¹ *a*¹¹ on the side of

the frame a^2 , as shown in Figs. 1 and 4. The shelves $a^{12} a^{12}$ are formed on the inner face of the bed a^2 to support the glue-pot f under the top a^4 and the cover a^9 ; as shown in Fig. 6. 5 On the two inner legs $a^3 a^3$ are formed the bearings $a^{13} a^{13}$ and on the two outer legs $a^3 a^3$ the bearings $a^{14} a^{14}$ and $a^{15} a^{15}$, as shown in Figs. 1 and 4. The part a' of the frame a consists of a bed a^{16} , having the ways $a^{17} a^{17}$ and 10 supported on the four legs $a^{18} a^{18}$, as shown in Figs. 1 and 4.

The gravity-hopper b for holding the spool-heads $m^4 m^4$ and supplying the same to the feed mechanism c by gravity consists of an inverted-U-shaped frame b' , having the two openings $b^2 b^2$ in the top and secured transversely to the top a^4 by the bolts $b^3 b^3$, as shown in Fig. 2. The two rods $b^4 b^4$, having the enlarged heads $b^5 b^5$, are suspended from the top of the frame b' through the openings $b^2 b^2$ by the heads $b^5 b^5$. These rods extend downward through the holes $m^5 m^5$ in the heads, the ends of the rods entering the next to the bottom heads, as shown in broken lines in Fig. 5, 25 leaving the bottom heads free to be removed in succession by the feed mechanism c . A cross-bar b^6 , having the slots $b^7 b^7$, is secured to the back of the frame b' adjacent the bottom by the bolts $b^8 b^8$, as shown in Fig. 3, and 30 the wings $b^9 b^9$ are adjustably secured to the inner face of the bar b^6 by the bolts $b^{10} b^{10}$ through the slots $b^7 b^7$ in the bar. An adjustable bar b^{11} , having the L-shaped ends $b^{12} b^{12}$, in which are the slots $b^{13} b^{13}$, is adjustably secured on the front of the frame b' opposite the bar b^6 by the bolts $b^{14} b^{14}$ through the slots $b^{13} b^{13}$. By this construction the hopper b is made adjustable for different size heads and 35 for centering the heads.

40 The feed mechanism c consists of the two slides $c' c'$, each constructed to reciprocate in the ways $a^6 a^6$ in the openings $a^5 a^5$ under the slide-heads $m^4 m^4$, as shown in Figs. 2 and 5. Each slide has the inwardly-extending tongue c^2 , bearing on the top a^4 of the frame and 45 constructed to have the steps c^3 and c^4 , forming the end c^5 and the shoulders $c^6 c^7$. A yoke c^8 is secured transversely above the ends $c^5 c^5$ of the slides to the top a^4 by the bolts $c^9 c^9$. The 50 bow-springs $c^{10} c^{10}$ are secured at their center to the yoke c^8 , the free ends of the springs bearing on the spool-heads, and the whip-springs $c^{11} c^{11}$ are secured at their fixed ends to the bar b^{11} , the free ends bearing on the 55 spool-heads. The guides $c^{12} c^{12}$ are adjustably secured to the cover a^9 by the bolts $c^{13} c^{13}$ in a position to guide the spool-heads and bring the holes $m^5 m^5$ in the heads over the circular holes $a^7 a^7$ in the top of the frame for 60 gluing the holes in the heads. By this construction the spool-heads are fed to the gluing mechanism d by the operation of the slides $c' c'$. A forward movement of the slides carries the spool-heads from the hopper b under the springs c^{10} and c^{11} , the tension of 65

the springs being sufficient to hold the heads on the return movement of the slides.

The gluing mechanism d consists of a frame constructed to have a cross-bar d' , with the bosses $d^2 d^2$ under the top a^4 in the glue-pot f , the ends $d^3 d^3$ of the cross-bar extending upward through the apertures $a^8 a^8$ in the top a^4 , the outwardly-extending portions $d^4 d^4$ and the downwardly-extending arms $d^5 d^5$ all formed integral, as shown in Fig. 6. The arms $d^5 d^5$ are further supported and guided by the straps $d^6 d^6$, secured to the sides of the frame a^3 . The glue-cups $d^7 d^7$ each have the circular cup-shaped head d^8 , the apertures $d^9 d^9$ in the side of the head, the circular flange d^{10} , and the downwardly-extending stem d^{11} , secured to the cross-bar d' through a hole in the boss d^2 by the set-bolt d^{12} , as shown in Fig. 7. A downward movement of the arms $d^5 d^5$ lowers the cross-bar d' with the glue-cups $d^7 d^7$ into the glue, as shown in broken lines in Fig. 6. An upward movement of the arms $d^5 d^5$ raises the cups filled with glue through the circular holes $a^7 a^7$ in the top a^4 and into the holes $m^5 m^5$ in the spool-heads $m^4 m^4$, as shown in full lines in Fig. 6. The glue is thus deposited on the surface of the screw-threaded holes $m^5 m^5$ in the bobbin-heads, assisted by the apertures $d^9 d^9$ in the side of the cups, and for a predetermined distance on the inner face of the heads by the flanges $d^{10} d^{10}$ on the glue-cups.

The actuating mechanism e consists of a driving-shaft e' , supported in the bearings $e^2 e^2$, secured to the floor. On the outer end of the shaft e' is secured the pulley e^3 and on the inner end the bevel gear-pinion e^4 . The shaft e^5 is supported in a bearing e^6 , secured to the floor at right angles to the bearings $e^2 e^2$. On the inner end of the shaft e^5 is secured a disk e^7 , having the bevel-gear e^8 on its back meshing with the bevel gear-pinion e^4 and the eccentric-pin e^9 on its face. The pulley e^3 and the disk e^7 revolve in the direction of the arrows, as shown in Fig. 1. A rock-shaft e^{10} is supported in the bearings $a^{14} a^{14}$, and to the inner end of the rock-shaft is secured an arm e^{11} , which in turn is pivotally secured at its free end to an actuating-arm e^{12} , having a notch e^{13} in its lower edge for the pin e^9 . On the rock-shaft e^{10} is secured a bell-crank lever e^{14} , the outer arm of which is pivotally secured to the lower end of the connecting-link e^{15} , which in turn is pivotally secured at its upper end to the outer arm of the bell-crank lever e^{16} , secured to a rock-shaft e^{17} , supported in the bearings $a^{15} a^{15}$ on the frame. The upper arm of the bell-crank lever e^{16} is pivotally secured to a connecting-arm e^{18} , which in turn is pivotally secured to a cross-shaft e^{19} , connected to lugs on the under side of the slides $c' c'$ of the feed mechanism c , as shown in broken lines in Fig. 1 and Fig. 2 and in full lines in Fig. 5. 120

The lower arm of the bell-crank lever e^{14} is pivotally secured to a connecting-bar e^{20} , which in turn is pivotally secured to the free end of an arm e^{21} , secured to the rock-shaft e^{22} , supported in the bearings $a^{13} a^{13}$ on the frame. On the outer ends of the rock-shaft e^{22} are secured the arms $e^{23} e^{23}$, to the free ends of which are pivotally secured the connecting-links $e^{24} e^{24}$, which in turn are pivotally secured to the lower ends of the arms $d^5 d^5$ of the gluing mechanism d . By this construction the feed mechanism c and the gluing mechanism d are operated when the actuating arm e^{12} is released and the pin e^9 engages with the notch e^{13} in the actuating-arm.

The glue-pot f is in the form of an open-top metal box, and the gas or steam jet g is placed under the glue-pot to keep the glue at the required temperature.

The head-stock h of the assembling mechanism consists of an inverted-U-shaped frame secured to the bed a^{16} and having the bearings $h' h'$ for a spindle h^2 . A pulley h^3 is secured to the spindle between the bearings $h' h'$, and on the inner end of the spindle is secured a face-plate h^4 , having the central pin h^5 , adapted to enter the hole m^5 in a spool-head and the hole m^2 in a spool-cylinder, and the chisel-shaped points $h^6 h^6$, adapted to engage with a spool-head and revolve the same.

The tail-stock i of the assembling mechanism is adjustably secured to the bed a^{16} on the ways a^{17} by a fastening-bolt i' in the usual way and has a longitudinal bore i^2 , in which is a spline i^3 , as shown in broken lines in Fig. 1. A reciprocating spindle i^4 , having the longitudinal groove i^5 , extends through the bore i^2 in the tail-stock. The spline i^3 engaging with the groove i^5 in the spindle prevents the rotation of the spindle. On the inner end of the spindle i^4 is secured a face-plate i^6 , having a central pin i^7 on a line with the pin h^5 for a spool-head and cylinder and the chisel-shaped points $i^8 i^8$, adapted to engage with the bobbin-head and prevent rotation of the head. The bifurcated fitting i^9 is secured to the outer end of the spindle i^4 by the set-nut i^{10} , as shown in Fig. 1. The tail-stock i is adjustable lengthwise on the bed a^{16} for different lengths of bobbins.

The release-arm k is adjustably secured at its upper end to the spindle i^4 by the set-bolt k' and extends downward through a slot in the bed. The lower L-shaped end k^2 of the release-arm extends toward the front of the machine under the outer end of the actuating-arm e^{12} , supporting the lever in its normal or inoperative position, as shown in Figs. 1 and 4. The operating-lever l is pivotally secured adjacent its inner end to the fitting i^9 on the spindle i^4 and at its inner end to the connecting-link l' , which in turn is pivotally secured to the bracket i^{11} on the tail-stock i . The operating-lever extends toward the front of

the machine over the top a^4 in a convenient position for the operator, as shown in Fig. 2.

In the operation of my improved spool gluing and assembling machine the operator removes the two glued bobbin-heads $m^4 m^4$ (shown in broken lines in Fig. 2) from the guides of the feeding mechanism and places them on the pins h^5 and i^7 of the assembling mechanism, as shown in broken lines in Fig.

1. A spool-cylinder m' is now placed on the pin h^5 between the bobbin-heads in a position for the pin i^7 to enter the hole in the cylinder. The operating-lever l is now moved forward toward the operator to move the face-plate i^6 toward the face-plate h^4 to screw the spool-heads onto the ends of the cylinder through the movement of the operating-lever l and the rotating of the face-plate h^4 in the direction of the arrow on the pulley h^3 , as shown in Fig. 1. As the operating-lever l is moved forward the L-shaped ends k^2 on the release-arm k moves forward to release the actuating-arm e^{12} . The eccentric-pin e^9 on the disk e^7 moving in the direction of the arrow, as shown in Fig. 1, now engages with the actuating-arm e^{12} through the notch e^{13} in the arm and through the arm e^{11} , the bell-crank lever e^{14} , the link e^{15} , the bell-crank lever e^{16} , and the arm e^{18} , and the cross-shaft e^{19} actuates to operate the feed-slides $c' c'$ of the feed mechanism c to deliver two spool-heads to the gluing mechanism and simultaneously through the connecting-bar e^{20} , the arm e^{21} , the arms $e^{23} e^{23}$, and the connecting-links $e^{24} e^{24}$, and the arms $d^5 d^5$ actuate to operate the gluing mechanism d to glue the screw-threaded holes $m^5 m^5$ in the spool-heads; thus feeding, gluing, and assembling a spool in one operation of the operating-lever l . The speed of the actuating mechanism e is less than the time required to operate the assembling mechanism by the operating-lever l . The return movement of the operating-lever brings the L-shaped ends k^2 of the release-arm k under the actuating-arm e^{12} , holding the actuating-arm in its inoperative position until the next forward movement of the operating-lever.

Having thus described my invention, I claim as new and desire to secure by Letters Patent—

1. In a spool gluing and assembling machine, a hopper adapted to feed spool-heads by gravity, a gluing mechanism adapted to glue a hole in the spool-heads automatically, a feed mechanism adapted to feed two spool-heads simultaneously from the hopper to the gluing mechanism, means for operating the feeding and the gluing mechanism, means for assembling a spool, and a lever for operating said last-named means, as described.

2. A spool gluing and assembling machine having a hopper for feeding spool-heads by gravity, a gluing mechanism adapted to glue a hole in two spool-heads simultaneously, a

feeding mechanism consisting of two slides adapted to feed two spool-heads simultaneously from the hopper to the gluing mechanism, means for operating the gluing mechanism, and the feeding mechanism consisting of an actuating mechanism having an actuating-arm operatively connected to the gluing and feeding mechanism, a release-arm adapted to hold the actuating-arm in its inoperative position, means for assembling a spool by screwing the heads onto the cylinder of the spool, and an operating-lever operatively connected with the release-arm and the assembling mechanism, as described.

15 3. A spool gluing and assembling machine having a hopper adapted to feed two spool-heads simultaneously by gravity, means for adjusting the hopper for different sizes of spool-heads, a gluing mechanism consisting of a glue-pot, a frame having glue-cups adapted to be raised and lowered into the glue-pot, means for heating the glue to the required temperature, a feeding mechanism consisting of two slides adapted to feed two spool-heads simultaneously from the hopper to the gluing mechanism, adjustable guides adapted to guide the spool-heads from the hopper to the gluing mechanism, means for operating the gluing and the feeding mechanism, means for assembling a spool by screwing the spool-heads onto the ends of the spool-cylinder, and an operating-lever operatively connected with the gluing, feeding, and the assembling mechanism, whereby the spool-heads are fed and glued automatically and a spool assembled in one operation of the operating-lever, as described.

4. In a spool gluing and assembling machine, an adjustable hopper adapted to feed
40 spool-heads by gravity, consisting of an inverted-U-shaped frame having two openings in the top, means for securing the lower ends of the frame to the frame of the machine, two rods having enlarged heads suspended from
45 the top of the inverted-U-shaped frame through the openings in the top and extending downward through holes in the spool-heads, the ends of the rods entering the next to the bottom heads, a cross-bar having slots
50 secured to the back of the inverted-U-shaped frame adjacent the bottom, wings adjustably secured to the inner face of the cross-bar by bolts through the slots in the cross-bar, a bar having L-shaped ends in which are slots adjustably secured on the front of the frame opposite the cross-bar by bolts through the slots in the L-shaped end of the bar, whereby the spool-heads are fed downward on the rods by gravity, and the hopper made adjustable
55 for different sizes of spool-heads, as described.

5. In a spool gluing and assembling machine, a gluing mechanism, an automatic feed mechanism consisting of two slides adapted to reciprocate in ways through openings in

the top of the machine, each slide having forwardly-extending tongues bearing on the top of the machine and steps forming shoulders on the slide, a yoke secured transversely above the forward ends of the slides to the 70 top of the machine, bow-springs secured to the yoke, guides adjustably secured to the top of the machine, and means for operating the feed mechanism, whereby two spool-heads are fed simultaneously from the hopper to the gluing mechanism of the machine, 75 as described.

6. In a spool gluing and assembling machine, an automatic gluing mechanism consisting of a glue-pot, means for holding the glue-pot under the top of the machine, means for heating the glue to the required temperature, a frame constructed to have a cross-bar with two bosses placed under the top of the machine in the glue-pot, ends on the cross-bar extending upwardly through apertures in the top of the machine, then outwardly and downwardly to form downwardly-extending arms guided by straps on the sides of the machine, glue-cups secured to the bosses on the cross-bar, each glue-cup having a cup-shaped head, apertures in the side of the head, a circular flange and a downwardly-extending stem, a removable cover for filling the glue-pot with glue, and means for operating the gluing mechanism to lower the glue-cups into the glue and raise the glue-cups filled with glue through holes in the top of the machine and into the holes in the spool-heads, whereby two spool-heads are glued simultaneously, 100 as described.

7. In a spool gluing and assembling machine having a feeding and gluing mechanism, means for operating the same consisting of an actuating mechanism having a driving-shaft supported in bearings, a pulley on the outer end of the shaft, a bevel gear-pinion on the inner end of the shaft, a shaft supported in bearings at right angles to the driving-shaft, a disk on the shaft, a bevel-gear on the back of the disk meshing with the bevel gear-pinion on the driving-shaft, an eccentric-pin on the face of the disk, a rock-shaft supported in bearings on the machine, an arm secured to the inner end of the rock-shaft, an actuating-arm pivotally secured to the free end of the arm on the rock-shaft and having a notch in its lower edge in a position to engage with the pin on the disk, means for holding the actuating-arm in its inoperative position and for releasing the same when required, a lower bell-crank lever secured to the rock-shaft, a link pivotally connecting the outer arm of the lower bell-crank lever to the outer arm of an upper bell-crank lever secured to a rock-shaft supported in bearings on the frame, means for connecting the upper bell-crank lever with the feed mechanism, a bar pivotally connecting the lower bell-crank lever with an arm secured to a rock-shaft support- 105 110 115 120 125 130

ed in bearings on the frame, arms secured to each end of the rock-shaft, and means for connecting the arms to the gluing mechanism, as described.

- 5 8. In a spool gluing and assembling machine, an assembling mechanism consisting of a bed supported on legs, a head-stock screwed to the bed and forming bearings for a spindle, a pulley on the spindle between the 15 bearings, a face-plate having a central pin and chisel-shaped points secured to the inner end of the spindle, a tail-stock adjustably secured to the bed and having a longitudinal bore in which is a spline, a reciprocating spindle in the bore of the tail-stock having a longitudinal groove for the spline, a face-plate on the inner end of the spindle having a central pin and chisel-shaped points, an operating-lever pivotally secured to the outer end 20 of the spindle and to a link which is pivotally secured to a bracket on the tail-stock, whereby a spool is assembled by screwing the spool-heads onto the ends of the spool-cylinder through a forward movement of the operating-lever and the rotating of the face-plate on the head-stock spindle, as described.

9. In a spool gluing and assembling machine, the combination of the frame *a*, the adjustable hopper *b* for feeding spool-heads 30 by gravity, the spool-head-feed mechanism *c*, the spool-head-gluing mechanism *d*, the actuating mechanism *e*, the glue-pot *f*, the heating device *g*, an assembling mechanism consisting of the head-stock *h* having the 35 spindle *h*², the pulley *h*³, the face-plate *h*⁴ with the central pin *h*⁵ and the chisel-shaped points *h*⁶ *h*⁶, and the tail-stock *i* having the bore *i*² with the spline *i*³, the reciprocating spindle *i*⁴ with the longitudinal groove *i*⁵ in 40 the bore *i*², the face-plate *i*⁶ with the central pin *i*⁷ and the chisel-shaped points *i*⁸ *i*⁸, the release-arm *k* adjustably secured to the spindle *i*⁴ and having the L-shaped lower end *k*², the operating-lever *l* pivotally secured to the 45 outer end of the spindle *i*⁴ and a link *l*' pivotally secured to the end of the operating-lever and to a bracket on the tail-stock *i*, as described.

10. In a bobbin gluing and assembling 50 machine, gluing mechanism, means for feeding spool-heads to said mechanism, assembling mechanism, and means for operating said assembling mechanism, said last-named means upon the inception of its movement 55 operating said gluing mechanism and said feeding means.

11. In a bobbin gluing and assembling

machine, gluing mechanism, means for feeding spool-heads to said mechanism, connected means for operating said gluing mechanism and said feeding means, means for assembling a spool by screwing the heads onto the cylinder of the spool, and means for operating said assembling mechanism, said last-named means having connection with 60 said connected means whereby the latter will be operated upon inception of movement of said means for operating the assembling mechanism.

12. In a bobbin gluing and assembling 70 mechanism, gluing mechanism, means for feeding spool-heads to said mechanism, means connected to said mechanism and said means for operating the same in unison, assembling mechanism, and means for operating 75 said assembling mechanism, said last-named means being connected to said means for controlling the operation of the gluing mechanism and the feeding means.

13. In a bobbin gluing and assembling 80 machine, gluing mechanism, means for feeding spool-heads to said mechanism, assembling mechanism means for operating said gluing mechanism and said feeding means in unison, and a pivoted element for controlling 85 the operation of said assembling mechanism, said element having connection with said means for operating the gluing mechanism and feeding means whereby each of the latter will be brought into action when said element is operated to actuate the assembling mechanism.

14. In a bobbin gluing and assembling machine, a gluing mechanism, means for feeding spool-heads to said mechanism, connected means for operating the gluing mechanism and feeding means in unison, assembling mechanism, a movable part which controls the operation of said assembling mechanism, and means connected to said assembling mechanism and operated by the movements of said part and connected to said connected means of the gluing mechanism and feeding means, whereby each of the latter will be operated upon inception of movement of said movable part to bring the assembling mechanism into action.

In testimony whereof I have hereunto signed my name to this specification in the presence of two subscribing witnesses.
